REVERSIBLE WINDOW

Le Roy B. Taylor, Cleveland, Ohio

Application January 31, 1938, Serial No. 187,793

2 Claims. (Cl. 189—67)

This invention relates to reversible windows and means for operating same and is an improvement on the window shown in my U. S. Patent No. 1,593,228.

One object of the invention is to provide a window of this type improved with respect to the means for supporting and reversing the sash.

Another object relates to the means for housing and connecting the pivoted arms and links which support the sash and for assembling such arms and links with respect to the window casing, so that the window may be fully reversed in such manner as to be sealed at the meeting rail, or merely reversed for washing when desired.

A further object is to generally improve the construction and assembly of such reversible windows and to simplify the method of operation as will more fully appear from the following description and the accompanying illustrations, 20 in which:

Fig. 1 is a fragmentary front elevation of the reversible window and its operating means as seen from the inside of the window with the housing removed.

Fig. 2 is a section taken on line 2—2 of Fig. 1. Fig. 3 is a section similar to Fig. 2 but showing the method of reversing and its operation.

Fig. 4 is an enlarged section on line 4—4 of Fig. 3, with the housing shown.

Fig. 5 is an enlarged section on line 5—5 of Fig. 2, with the housing shown.

Fig. 6 is an enlarged section on line 6—6 of Fig. 2, with the housing shown.

Fig. 7 is an enlarged fragmentary section similar to Fig. 2 but showing the completely reversed sash in dot-dash lines.

Again referring to the illustration; this improved reversible window comprises a casing 10 constructed preferably of sheet steel or the like, 40 having grooves 11 wherein are mounted adjustable weatherstripping 12 secured to the sash 13 by screws 12a. A guide housing 14 mounted inside of the casing 10 and on the inner side of the casing stiles has a series of slots therein. These 45 slots comprise a narrow slot 15, adjacent the top of the housing 14, which extends downward to a shoulder 15a where it terminates in slot 16 which is substantially double the size of the slot 15, and slot 16 also extends downward to a 50 shoulder 17 at which point said slot terminates in a second narrow slot 18.

In a groove or channel 19 formed between the casing 10 and the housing 14, is mounted an arm 20, said arm having secured on each side thereof, 55 adjacent its top end, rollers 21 and 22 upon a

pivot 23 secured through said arm 20, as specifically illustrated in Fig. 4; these rollers will run up or down in the guide housing 14.

The lower end of arm 20 terminates in an ear 24 having a pivot 25 mounted therethrough and 5 pivotally secured to the sash 13.

A second arm or link 26 is pivotally secured to each arm 20 by a pivot 27 at its upper end, its lower end being secured pivotally to the casing 10 by a pivot pin 28; an aperture 29 in the guide 10 housing 14 allows access to the pin 28 for assembly; a reinforcing block 14a is secured to frame 10 by the pin 28 at which point the arm pivots and the pivot 25 registers with a slot 30 in the housing 14 and slides therein when the sash 15 is closed as shown in Figs. 1, 2, and 7. A glass or pane 31 is secured between the sash 13 and a glass stop 31a.

In reversing the sash 13, the arms 20 swinging out through the slots 15 pivot at their upper 20 ends on the pins 28 as the rollers 21 and 22 move downward in the grooves or channel 19 between the guide housings 14 and the casing 10; the link arms 26 pivoting at their lower ends on the pivot pins 28 with the outward movement of 25 the arms 20 also swings outward through the slots 17 in the guide housings 14, the top of link arms 26 and the bottom of arms 20 pivoting together, swing out of slots 16, the pivots 25 moving outward through slots 30 in the housing 14 30 adjacent to the opening into slot 16 thus swinging the window from a vertical to a horizontal position, then as the arms 20 and link arms 26 move back to their original positions, the bottom of the said window swings upward to assume the 35 top position as indicated by dot-dash lines "A" in Fig. 7, the outside of the glass or pane 31 now being on the inside. The sash pivot 41 Fig. 6, moving vertically up and down in the channel 19a formed between the housing 14 and the 40 casing 10.

I claim:

1. In a reversible window the combination of an outer casing having stiles each shaped to form a flange on the inner side of the window and a 45 vertical channel intermediate its width, a guide housing extending vertically beside each stile, said housing having an inner flange overlying the flange of the stile on the inside of the window, the inner edge of the housing being bent to form 50 an angle which fits within the channel of the stile, the intermediate portion of the housing being spaced from the stile to form a vertical chamber, the said inner flange of the housing having a vertical slot communicating with said 55

chamber, a reversible sash fitting between the housing, a pair of swinging arms provided at one end with rollers which travel up and down in the channels of the housings and pivoted at the other end to the sash, and a pair of links

5 pivoted at opposite ends to the arms and stiles

respectively, said arms and links swinging through said slots when the sash is reversed.

2. The combination stated in claim 1, the housings having grooves to receive the sash pivots when the sash is closed.

LE ROY B. TAYLOR.
